LOCK

Filed March 1, 1945

UNITED STATES PATENT OFFICE

2,481,093

LOCK

Louis M. Dyson, New Britain, Conn.; Beatrice N. Dyson, administratrix of said Louis M. Dyson, deceased, assignor to The American Hardware Corporation, New Britain, Conn., a corporation of Connecticut

Application March 1, 1945, Serial No. 580,384

11 Claims. (Cl. 70—369)

1

This invention, while particularly adapted for use in a padlock, may be embodied in various forms of locks, but by reason of its adaptability to a padlock such a structure is shown for the purpose of disclosing the invention herein.

An object of the invention, among others, is the production of a lock comprising a unit in which much of the locking mechanism is contained and which may be, by the use of a proper key, removed from the lock body as a whole either for insertion in another lock body or for the purpose of changing parts of the lock mechanism.

Another object of this invention is to provide a lock which is operable by a service key and a master key and which, in addition, has a removable insert unit which can be removed from the lock shell by means of a third, or special, key which may also be used for operating the lock; this differing materially from previously known locks which do not provide for the use of a master key which is not operable for removing the insert unit and therefore provided only for the use of a service key besides the key which is required for removing the insert unit. The present invention provides for the use of a service key and a master key besides the key required for removal of the insert unit.

One form of a padlock embodying my invention and in the construction and use of which the objects herein set out, as well as others, may be attained is illustrated in the accompanying drawing, in which—

Figure 1 is a side view of a lock embodying my invention.

Figure 2 is an edge view of the same.

Figure 3 is a view in central vertical section on a plane denoted by the broken line 3—3 of Fig. 4.

Figure 4 is a view looking at that end opposite the shackle.

Figure 5 is a view in section on a plane denoted by the broken line 5—5 of Fig. 3.

Figure 6 is a view in section on a plane denoted by the broken line 6—6 of Fig. 3.

Figure 7 is a view in central vertical section through the removable unit.

Figure 8 is a view in cross section through said unit illustrating the stop pin in position for permitting operation of the master sleeve and thereby by the insert releasing key to release the insert unit.

Figure 9 is a view in cross section through the insert unit showing the parts with the key plug in position for operating the lock in the usual manner.

Figure 10 is a view in vertical central section

2 through a lock showing a modification of the invention.

In the accompanying drawings the numeral 10 denotes the body or shell of a lock that is, as hereinbefore mentioned, in the form of a padlock, this body having a hole comprising a well 11 on one side to receive the long leg 12 of the shackle and an opening 13 on the opposite side or edge of the shell at the end thereof to receive the short leg 14 of the shackle. The long leg 12 of the shackle is seated at its inner end upon a spring 15 and an elongated notch 16 on the side of the shackle receives a retaining pin 17 that prevents removal of the shackle from the case and particularly under the force of the spring 15. Locking notches 18—19 are formed in the long and short legs of the shackle to receive locking bolts 20 to be hereinafter more fully described.

Said body is bored from the bottom end to provide a recess 21 extending inwardly near to the opposite or top end of the case to receive an insert unit 22 in which is contained much of the mechanism of the lock such as the key plug, bolt, bolt spring, pin tumblers, drivers, master pins, tumbler springs, etc., which parts are well known to those skilled in the art and to which no particular reference, except as will be hereinafter specifically mentioned, will be made herein. This recess conforms somewhat to the shape of a figure 8 in cross section and comprises a key plug chamber 23 and a somewhat smaller tumbler chamber 24 to receive similar parts 25—26, respectively, of the insert unit 22. This insert unit comprises the part 26 which is in fact a body for support of pin tumblers 27, and integral with said body is a sleeve portion 28 within which a master sleeve 29 is fitted to turn. This insert also comprises a key plug 30 provided with a key slot and with tumblers in a manner common to pin tumbler locks. An insert retainer, having a ring shaped portion 31 and a tongue 31—a, is rotatably mounted on the inner end of the plug 30 and is adapted to enter a slot 32 cut into the case to receive said tongue. The said tongue projects through a notch 31—b in the end of the master sleeve, which permits clockwise movement of said sleeve and plug without rotation of the retainer when in locked position, as shown in Fig. 6; the said retainer being held in said locked position by means of a pin 31—c which is pressed upwardly by a spring, not shown. The master sleeve 29 may be rotated in counter-clockwise direction by the use of the proper key, to be presently described, and the insert then removed from the lock body. The said master sleeve is provided with a stop pin 33

adapted to enter a groove 34 extending circumferentially in the plug 30, thereby permitting the plug to have a clock-wise movement by the use of a proper key to operate the bolt and release the shackle to unlock the lock.

The sleeve portion 28 of the insert unit is provided with a slot 35 into which a floating pin 36 carried by the master sleeve 29 will enter when pushed out by the service key. This pin will block the counter-clockwise movement of the plug and the master sleeve but will allow a clock-wise movement of the plug and master sleeve to effect operation of the lock to release the locking bolt. Prevention of counter-clockwise movement of the plug and master sleeve by the pin 36 ensures no chance for operation to release the insert unit by use of the regular service or master keys, as insertion of these keys will force the pin 36 outwardly into the slot 35 and thereby prevent the use of such keys for releasing said unit. The special key 37 has a notch 38 as shown in Fig. 7 to clear the floating pin 36 and thereby allow the pin to move out of the slot 35 upon rotation of the master sleeve and permit counter-clockwise movement of the master sleeve to release the insert retainer and permit removal of the insert unit.

The hub of the locking bolt 20 is provided with a recess 39 into which the end of the plug 30 enters for operation of said locking bolt, the unlocking movement being obtained by operation of the plug and locking movement being effected by means of a spring, not shown herein.

That form of the lock shown in Fig. 10 is similar to that hereinbefore described except that the locking bolt comprises a part of the insert unit and is removed with that unit. This unit comprises the key plug and tumbler parts with the key plug, master sleeve, and enveloping sleeve 28 and for this reason such parts are identified by the same characters as in the preceding figures and the same keys are employed for operating the key plug in the usual manner and for operating the master sleeve.

The locking bolt 40 is slidably mounted in a chamber 41 with its nose 42 adapted to engage the notch in the end of the short leg 14 of the shackle and with a notch 43 in its under surface within which a cam lug 44 projecting from the end of the key plug 30 enters for the purpose of operating the bolt, the lug moving the bolt backwardly to release the shackle and a spring 45 acting upon the bolt to move it into locking position.

It will be seen, from the foregoing description, that a service, or regular key, is used to operate the tumblers and turn the key plug 30 so as to operate the lock bolt 20 to release the lock. A master key may be used to operate the tumblers so that the master sleeve 29 may be released by the tumblers to permit rotation of said sleeve and the plug 30 to thereby operate the bolt with the said master key in the same manner as it is operated by the regular or service key. In addition, the special or insert key 37 may be used for rotating the master sleeve counter-clockwise, as above described, to operate the retainer for removing the insert from the shell 13.

It will be further understood that the notch 31-b provides lost motion between the master sleeve and the retainer will permit clockwise movement of the master sleeve and plug 30 to operate the bolt for releasing the shackle 14 without operating the retainer tongue 31-a. The provision of said lost motion between the

master sleeve and retainer provides for the use of a service key and a master key which are incapable of operating the retainer 31; therefore rendering it necessary that a special key be used before the insert may be removed from the lock shell.

I claim:

1. A lock comprising a body having a chamber shaped to receive an insert unit, a locking bolt movably mounted within said body, an insert unit fitted for housing in said chamber and comprising a shell, a master sleeve rotatably mounted in said shell and having a retainer projecting to enter a recess in said body, a key plug rotatably mounted in said sleeve and having a key slot to receive a key for rotation of the plug, means engageable with a formation on said key to permit rotation of said sleeve in one direction only, means on said sleeve engageable with a formation on said plug to permit rotation of the plug in one direction only, and an operative connection between said locking bolt and sleeve.
2. A lock comprising a body having a chamber, a locking bolt movably mounted within said body, an insert unit fitted for housing within said chamber and comprising a shell, a master sleeve rotatably mounted in said shell, a key plug rotatably mounted in said sleeve and having a key slot to receive a key for operation of the plug, a retainer mounted on said plug and operable by rotation of said sleeve, means for operatively connecting said sleeve and plug, and an operative connection between the locking bolt and plug.
3. A lock comprising a body having a chamber, a locking bolt movably mounted within said body, an insert unit fitted for housing within said chamber and comprising a shell, a master sleeve rotatably mounted in said shell, a key plug rotatable in said sleeve and having a key slot to receive a key for operation of said plug, a retainer rotatable on said plug and projecting therefrom to enter a recess in said body, means including a notch in said sleeve for operating said retainer, means operable with said key for operatively connecting said sleeve and plug, and an operative connection between said locking bolt and plug.
4. A lock comprising a body having a chamber, a locking bolt movably mounted within said body, an insert unit fitted for housing within said chamber and comprising a shell, a master sleeve rotatable within said shell, a key plug rotatable within said sleeve and having a key slot to receive a key for operation of said plug, a retainer rotatable on said plug and projecting through a portion of said sleeve to enter a recess in said body, a lost motion connection between said sleeve and retainer for operating the retainer, means operable with said key for operatively connecting said sleeve and plug, and an operative connection between said locking bolt and plug.
5. A lock comprising a body having a chamber, a locking bolt movably mounted within said body, an insert unit fitted for housing within said chamber and comprising a shell, a master sleeve rotatable within said shell and having a notch in an end portion thereof, a key plug for operating said bolt rotatable within said sleeve and having a slot to receive a key for operation of said plug, a retainer rotatable on said plug and having a tongue projecting through said notch to enter a recess in said body, and an operative

connection between said key plug and sleeve; the said sleeve being movable in one direction with said plug independently of said retainer to permit operation of the bolt by said plug, and the said sleeve being movable in an opposite direction for operating said retainer to release said insert.

6. A lock comprising a body having a chamber therein, a locking bolt movably mounted within the body, an insert unit fitted for housing within said chamber and comprising a shell, a master sleeve rotatably mounted within said shell and having a notch in an end portion thereof, a key plug for operating said bolt rotatable within said sleeve and having a key slot to receive a key for operation of said plug, a retainer rotatable on said plug and having a tongue extending through said notch to enter a locking recess in said body, and an operative connection between said key plug and sleeve; the said notch providing lost motion between said sleeve and retainer to permit turning of the said sleeve with said plug for operation of the bolt independently of said retainer.

7. A lock comprising a body having a chamber therein, a locking bolt mounted within said body, an insert unit fitted for housing within said chamber, and comprising a shell, a master sleeve rotatable in said shell, a key plug for operating said bolt rotatable in said sleeve and having a key slot to receive a key for operation of the plug, a retainer rotatable on said plug and having a tongue projecting through an opening in said sleeve to enter a recess in said body; the said opening providing a lost motion connection between said sleeve and retainer for operation of the retainer and for permitting partial rotation of the sleeve independently of the retainer, and a detent for releasably securing said retainer in position.

8. A lock of the character described, as set forth in claim 7, wherein the said detent comprises a movable pin in the insert engageable with the tongue of said retainer for holding the retainer in position to lock the insert to the body or to permit removal of the insert from the body.

9. A lock comprising a body having a chamber therein, a locking bolt movably mounted within said body, an insert unit fitted for housing within said chamber and comprising a shell, a master sleeve rotatable in said shell, a key plug rotatable within said sleeve, a retainer operable by said sleeve and projecting to enter a recess in said body, the said shell having a slot therein, a pin slidably in the wall of said sleeve and projecting into said slot and thereby permitting

clockwise movement of said sleeve but preventing counter-clockwise movement thereof, an operative connection between said sleeve and retainer permitting said clockwise movement of the sleeve independently of the retainer, and means including a notch in a special key for permitting withdrawal of said pin from the slot in the shell to permit counter-clockwise rotation of the master sleeve for operation of the retainer to unlock position.

10. A lock of the character described comprising a body having a chamber therein, a locking bolt movably mounted within said body, an insert unit fitted for housing within said chamber and comprising a shell, a master sleeve rotatably mounted in said shell, a key plug rotatable in said sleeve and having a key slot to receive a key for operation of the plug, a retainer rotatable on said plug and projecting through a portion of said sleeve to enter a recess in said body, an operative connection between said locking bolt and plug, and a lost motion connection between said retainer and sleeve for operation of said retainer; said lost motion connection permitting rotation in one direction of said master sleeve with said plug, for operation of said bolt when the said retainer is in insert locking position, and unlocking movement of said retainer upon rotation of said sleeve in an opposite direction.

11. A lock comprising a body having a chamber therein, a locking mechanism, an insert unit fitted within said chamber and comprising a shell, a master sleeve rotatably mounted in said shell, means for removably securing said sleeve within said shell, a master key fitting said sleeve for sole and independent operation thereof in one direction to secure and release said unit, a separate master key fitting said sleeve for sole and independent operation thereof in an opposite direction to operate said locking mechanism, and a key plug rotatable within said master sleeve independently thereof and adapted to receive a key for its operation independent of said master sleeve.
